UNITED STATES PATENT OFFICE.

WESTON A. PRICE, OF CLEVELAND, OHIO, ASSIGNOR TO THE ELECTRIC AND DENTAL SPECIALTY COMPANY, OF CLEVELAND, OHIO, A CORPORATION OF OHIO.

ELECTRICAL MEASURING INSTRUMENT.

SPECIFICATION forming part of Letters Patent No. 783,733, dated February 28, 1905.

Application filed February 24, 1903. Serial No. 144,611.

To all whom it may concern:

Be it known that I, WESTON A. PRICE, a citizen of the United States, and a resident of Cleveland, county of Cuyahoga, and State of Ohio, have invented a new and useful Improvement in Electrical Measuring Instruments, of which the following is a specification, the principle of the invention being herein explained and the best mode in which I have contemplated applying that principle, so as to distinguish it from other inventions.

My invention relates to instruments for measuring electrical currents, and particularly to milliammeters used in dental cataphoresis. The said invention has for its object the provision of an ammeter of such delicacy of construction and operation as will permit electrical currents of exceedingly small amperage to effect a movement on the part of the indicating means connected therewith of comparatively large amplitude, so that readings of thousandths of milliamperes, hundredths of milliamperes, tenths of milliamperes, milliamperes, as well as amperes, may be made with facility and accuracy.

The said invention consists of means hereinafter fully described, and particularly set forth in the claims.

The annexed drawings and the following description set forth in detail certain mechanism embodying the invention, such disclosed means constituting but one of various mechanical forms in which the principle of the invention may be used.

In said annexed drawings, Figure I represents a plan view of a milliammeter embodying my invention, a part of the casing or cover being illustrated as broken away in order to disclose the mechanism. Fig. II represents a vertical central longitudinal section of said milliammeter, parts cut by the plane of section being illustrated in elevation. Fig. III represents a vertical transverse section taken upon the plane indicated by the lines 3 3 in Figs. I and II and viewed in the direction indicated by the arrows in said figures.

A base member A, preferably of wood or other non-conducting material, has secured

thereon in a suitable manner a casing or cover B, which incloses substantially all of the mechanism embodied in the instrument. In the central portion of this base and intersecting the upper surface thereof is formed a depression a for receiving the lower member of a sectional permanent magnet C, which is secured to the base by means of a plate c and a screw c'. Two concave pole-pieces c² c² are secured upon the inner surface of the free ends of the magnet, and upon the back of these pole-pieces is secured, by means of screws c³, a supporting-piece c⁴, formed with a lug c⁵, projecting between the said two pole-pieces, as shown in Figs. I and II. To the inner surface of said lug is secured, by means of a screw c⁶, a soft-iron cylindrical core C', coaxial with the concave surface of the pole-pieces. The upper base of such core is intersected by a centrally-located cylindrical bore c⁷, from which projects a needle-point c⁸, fixed to the core, as shown in Fig. III. Upon this needle-point is supported an armature consisting of a coil D of insulated wire wrapped upon a suitable frame d. This frame has secured to it and projecting from the under surface of its upper portion a centrally-located bearing d', in which is journaled the needle-point. It will hence be seen that the coil is mounted to swing freely in suspension in the annular space between the pole-pieces and core, the needle-point forming its sole support. Upon the upper surface of the pole-pieces are secured four headed pins e e, two on each pole-piece, Fig. I. These pins form a bearing for an annular ring E, provided with a rearwardly-projecting handpiece e', which projects through an aperture b in the cover B. This aperture is covered by a sliding plate b', provided with an opening for permitting the passage therethrough of the handpiece e', and is held in position by a helical spring e², mounted upon such handpiece intermediately of said plate and the ring E, as shown. Such plate in so closing such opening permits of the partial rotation of the ring and at the same time prevents dust, &c., from entering the cover through opening b. Upon

this ring E is secured an upright curved stud e^3 , to the upper end of which is secured the outer end of a spiral retractable spring e^4 , the inner end of which is secured to an axial pinte d^2 , secured to the frame d , Fig. III. The pins e are placed so as to exert an amount of frictional contact upon ring E, such as will prevent same from having its position unpremeditatedly altered after having been given

- 10 a required position. The lower end of the frame is provided with a downwardly-projecting axial pinte d^3 , to which is secured the inner end of a very sensitive spiral spring e^5 , the outer end of which is secured to a clip f ,
- 15 secured to an insulated screw F, projecting from and secured to the one pole-piece of the magnet, as shown in Fig. III. Said spring e^5 is of a trend opposite that of spring e^4 , the relaxation being thereby neutralized, and serves
- 20 to steady and balance the coil. One end of the latter is electrically connected with pinte d^2 and the other end with pinte d^3 , and the pole-pieces, ring E, stud e^3 , spring e^4 , coil-pinte d^2 , coil-spring e^5 , clip f , and screw F are
- 25 all connected electrically in series.

Two binding-posts G and H are provided and secured to the base A upon opposite sides of the cover B, as shown in Fig. I. Post G is connected by a wire conductor g (shown in dotted lines in Fig. I) with the plate c. Post H is connected by a similar conductor h with the screw F. Post G is further connected by a second conductor g' (shown in dotted lines in Fig. I) with one end of a series of conductors $J^1 J^2 J^3 J^4 J^5$ of varying resistance. The other end of each such conductor is connected by means of separate conductors j^1, j^2, j^3, j^4 , and j^5 with one of a series of plug-seats 1, 2, 3, 4, and 5. A plug K is connected by means of a

- 30 40 flexible conductor k with the binding-post H.

The front of the cover B is downwardly inclined and provided with an opening b^2 , covered with glass. Behind such opening is secured a scale M, suitably divided and marked.

- 45 Secured to the upper portion of the coil-frame d is an indicating-pointer L, the point of attachment lying, as shown, substantially in the plane intersecting the plane of the needle-point—that is, the point of support of the coil
- 50 and parallel with the direction of movement of the coil. Upon the side of the upper frame portion opposite that to which the pointer is secured is an adjustable weight l , counterbalancing the weight of the pointer.

- 55 The above-described construction, owing to the presence of a minimum amount of frictional resistance on the part of the means supporting the coil, is exceedingly sensitive to currents of extremely small amperage, so that
- 60 a very considerable movement of the pointer is obtained by relatively small variations in the current passing through the coil.

In operation the terminals of the line are secured to the binding-posts G and H and

- 65 the current passes through the conductor g ,

plate c, magnet C, ring E, stud e^3 , spring e^4 , pinte d^2 , coil D, pinte d^3 , spring e^5 , clip f , screw F, and so to the binding-post H. In practice I use a scale about eight inches in length divided into fifty subdivisions. A current of one-twentieth of a milliamperes passing through the mechanism will effect a movement of eight inches on the part of the end of the pointer, so that a variation of one-thousandth of a milliamperes will effect a movement of one-fiftieth of eight inches, or eight-fiftieths of an inch, or approximately one-sixth of an inch.

When it is desired to measure a current of greater strength than one-twentieth of a milliamperes, the plug K is inserted in seat No. 1, and the variable resistance J' so shunted into the circuit, the other resistances being shunted into the circuit as is desired, the sizes of such variable resistances being relatively 85 decimal parts of each other. This resistance J' illustrated I prefer to arrange so as to be one to nine as compared with the resistance of the mechanism. Under such conditions but one-tenth of the current is effective and 90 the readings on the scale are taken in tenths and hundredths of milliamperes. The instrument is made ten times as sensitive as the above by means of six plug-seats each connected with and similar to h , producing a scale 95 measuring accurately a current of one-millionth of an ampere to ten amperes. In order to adjust the pointer so as to cause its end to rest normally upon zero, the current is cut off, and the retractile force of spring e^4 is 100 varied by turning the ring E, by means of the projecting handpiece e' , until such desired position of the pointer is secured. In case 105 circumstances and conditions are such as to render the normal zero-point difficult to see, the zero-point may be moved by such variation of the force of the spring to an intermediate position on the scale so as to overcome such difficulty.

It is desirable when the instrument is not resting upon a fixed support, as when being carried about, to provide means for securing the coil, and hence the pointer, against movement during such time. To this end I provide a plunger N, Fig. II, which is actuated to project or tend to be projected from the bottom of the base a short distance by a helical spring n . The upper end of this plunger articulates with the end of a lever n' , whose other end carries a ring n^2 , which is located immediately 110 below the frame d of the coil. The spring n is of such a strength that the weight of the instrument will effect its compression and depress the ring n^2 into the position shown in Fig. II. When the instrument is lifted off 115 the support, said spring actuates the plunger to operate the lever n' to raise the ring, cause it to engage the lower surface of the frame d , and effect contact between the latter and the core C'. In such position the coil and pointer 120

are held in a fixed position against vibration, so preventing any possible injury to the bearing.

Other modes of applying the principle of my invention may be employed instead of the one explained, change being made as regards the mechanism herein disclosed, provided the means stated by any one of the following claims or the equivalent of such stated means be employed.

I therefore particularly point out and distinctly claim as my invention—

1. In a measuring instrument, a suitable base, a magnet supported thereon, a coil mounted and movable in the field of force of said magnet, an indicating-pointer secured thereto, means for steadyng said coil, means for moving the same independently of the variations of the field of force, and means for securing the same against movement when the instrument is removed from a fixed support.

2. In a measuring instrument, a magnet, a conductor mounted and movable in the field of force of the same, a shunt-circuit comprising a plurality of electrical resistances of varying values, means for shunting any or all of such resistances between the terminals of said conductor, an indicating-pointer secured to the latter, a single bearing for supporting said conductor, and means for lifting said conductor, from said bearing and securing it against movement when the instrument is removed from a fixed support.

3. In a measuring instrument, the combination of a movable member and suitable supporting means therefor, an inclosing casing, an indicating-pointer connected with said member, a retractile spring connected with each end of the latter, the trend of one of said springs being opposite to that of the other, a ring connected with one of said springs and normally secured against rotation, and a suitable handpiece connected to said ring, projecting from said casing, and adapted upon its actuation to rotate said ring to vary the retractile strength of said spring.

4. In a measuring instrument, the combination of a base, a rotatable member mounted thereon, an indicating-pointer secured to said member, means projected from the bottom of said base arranged to be actuated by the weight of the instrument, and connected with said movable member in such a manner as to secure the same against rotation upon being released from the weight of the instrument.

50

55

5. In a measuring instrument, the combination of a base, a rotatable member mounted thereon and movable from off its bearing, an indicating-pointer secured to said member, means projecting from the bottom of said base arranged to be actuated by the weight of the instrument, said means being connected with said movable member in a manner such as when released from the weight of the instrument to lift said member from its bearing and secure it against rotation or movement.

60

6. In a measuring instrument, a base, a magnet, a conductor mounted and movable in the field of force of the latter, a shunt-circuit comprising a plurality of electrical resistances of varying values, means for shunting any or all of such resistances between the terminals of said conductor, an indicating-pointer secured to the latter, a single bearing for supporting said conductor, a plunger in the bottom of said base, a spring for actuating said plunger out from said base when the instrument is lifted from a fixed support, said spring being normally compressed by the weight of the instrument, a lever actuated by the outward movement of said plunger, and a ring actuated upwardly by the movement of said lever and adapted to contact with and lift said conductor from its bearing and secure same against rotation or movement.
